UNITED STATES PATENT OFFICE.

HENRY W. GRIFFIN, OF NEW YORK, N. Y., ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,298,693.

Specification of Letters Patent.

Patented Apr. 1, 1919.

Application filed March 4, 1912. Serial No. 681,606.

To all whom it may concern:

Be it known that I, HENRY W. GRIFFIN, a citizen of the United States, residing at New York, in the county of New York and State of New York, have invented certain new and useful Improvements in Railway Signaling, of which the following is a specification.

My invention relates to signaling for single track over which traffic moves in both directions; it is particularly adapted for signaling of stretches of single track between passing sidings, although it is not limited to this particular application.

I will describe one form of railway signaling system embodying my invention, and then point out the novel features thereof in claims.

In the accompanying drawing Figure 1 is a diagrammatic view showing a stretch of track provided with one form of signaling system embodying my invention. Fig. 2 is a diagrammatic view showing a modification of the form shown in Fig. 1. Fig. 3 is a diagrammatic view showing a duplication of the units shown in Fig. 1. Fig. 4 is a diagrammatic view showing another modification of Fig. 1.

Similar reference characters refer to similar parts in each of the views.

Referring first to Fig. 1, A designates a stretch of single track. B and C are two passing sidings. P is a preliminary section for purposes hereinafter explained. The stretch A is provided with signaling devices adjacent each siding for governing traffic in opposite directions through the stretch. Each signaling device is adapted to indicate "danger," "caution," and "clear."

As here shown each signaling device comprises a semaphore S or S' adapted for two positions of indication and an auxiliary signal L or L' here shown as being electric lamps. I do not however wish to be limited to this particular type of signaling device. It is understood that each semaphore S and S' is also provided with a light in the usual manner for night indications.

Semaphore S is controlled by relay D, semaphore S' is controlled by relay D'. These relays I shall hereinafter refer to as the "clear indication" relays. Lamp L is controlled by relay E, and lamp L' is controlled by relay E'. These latter relays I shall hereinafter refer to as the "caution indica-

tion" relays. The semaphore S is also controlled by a relay H which I will hereinafter term "an auxiliary signal relay" and which permits semaphore S to change to clear when an east-bound car or train passes entirely off of stretch A into section P, but which permits a west-bound car or train to change semaphore S to danger when it enters section P.

The stretch A is provided with at least two track relays arranged to be operated successively by the passage of a car or train through the stretch. As here shown the stretch A comprises one track circuit having a source of alternating signaling current connected adjacent the middle and two track relays a and b connected adjacent the end. The source of signaling current is as here shown, a transformer T whose secondary is connected with the track rails and whose primary is connected with line wires 12 which are supplied with alternating signaling current by any suitable means, as by a generator G. The preliminary section P is also provided with a track circuit which is supplied with signaling current from the line wires 12 through a transformer T', and which includes a track relay c.

The track relays a, b and c are adapted to respond to alternating signaling current, and if electric propulsion current is employed these relays are preferably such as will respond to the signaling current and not to the propulsion current. Relays of these types are well known in the art and need not be explained or illustrated in detail herein.

Each semaphore S and S' is provided with a controlling circuit, which circuit is in turn controlled by the corresponding clear indication relay D or D'. The circuit for semaphore S is from battery 10 through wire 16, armature contact 17 of relay D, wire 18, semaphore S, wire 19, to battery 10. The circuit for semaphore S' is from battery 11 through wire 20, armature contact 21 of relay D', wire 22, back contact of armature contact 23 of relay E', wire 24, semaphore S', wire 25, to battery 11. Each lamp L and L' is also provided with a controlling circuit which circuits are controlled by caution indication relays E and E'. The circuit for lamp L is from battery 10, through wire 26, armature contact 27 of relay E, 110

wire 28, lamp L, wire 19, to battery 10. The circuit for lamp L' is from battery 11, through wire 29, armature contact 30 of relay E', wire 31, lamp L', wire 25, to battery 11.

When no car or train is present in the stretch A, the clear indication relay D is energized by the following circuit:—from battery 11, through wire 29, back contact of 10 armature contact 30 of relay E', wire 32, circuit controller 15, wires 33 and 34, armature 35 of track relay c, wire 36, armature 37 of track relay b, wire 38, armature 39 of track relay a, wire 40, relay D, wire 41, common 15 wire 42, to battery 11. Assume now a car or train enter the stretch A from the west end: Track relay a is first opened, thereby opening the circuit of relay D at armature contact 39. Relay D is provided with a front 20 contact 44 which is so constructed that it remains closed until just before the relay armature has reached its full open or deenergized position; as here shown, this is accomplished by means of a flexible spring 44^a fixed on the 25 contact finger and employed as the contact itself. Hence, when relay D is deenergized by the opening of track relay a, contact 44^a remains closed until after contact 39 reaches its back contact 39^a. During the interval between the closing of contact 39—39^a and the 30 opening of contact 44, an energizing circuit for relay E is closed, which circuit is the same as that just traced for relay D as far as armature 39, and is then through wire 43, 35 armature contact 44 of relay D, wires 45 and 46, relay E, wires 47 and 42 to battery 11. Relay E is thus energized and closed. Relay D is also provided with a back contact 17^a which, when the relay is deenergized, closes 40 before the front contact 44^a opens. As soon as the back contact 17^a closes, a holding or stick circuit is closed through relay E as follows: from battery 10, through wire 16, back contact 17^a, wire 48, armature contact 45 49, wire 46, relay E, wires 47 and 42, to battery 10. When relay D becomes fully opened so that contact 44^a opens, the energizing circuit for relay E is opened at this point, but 45 relay E remains energized by the holding or stick circuit just traced. The opening of relay D of course opens the circuit of semaphore S and this semaphore therefore changes to danger indication. The closing of relay E closes the circuit of lamp L which 50 therefore becomes illuminated thereby indicating to following trains to proceed through the stretch A under caution.

As the car or train proceeds through the stretch A past the point of connection of the 60 source of signaling current with the track rails, it opens track relay b, thereby holding open the circuit of relay D, relay D therefore remains open and relay E remains closed, thereby maintaining the indication 65 of semaphore S and lamp L.

The opening of track relay b closes an energizing circuit for auxiliary signal relay H as follows: from battery 11, through wire 50, armature contact 51 of track relay c, wire 52, back contact 53 of track relay b, wire 54, 70 relay H, wire 55 to battery 11. As the car or train proceeds into preliminary section P, it opens track relay c thereby closing a holding or stick circuit for relay H, which circuit is from battery 11, through wire 50, back contact 75 of armature contact 51, wire 56, armature contact 57, wire 58, relay H, wire 55 to battery 11. When the entire car or train leaves the rails of stretch A, track relay b again closes, but track relay c is open and 80 this would hold open the circuit of relay D at contact 35, thereby holding semaphore S at stop, were it not for the fact that relay H is now closed forming a shunt around armature contact 35 of track relay c, which shunt 85 is through wire 59, armature contact 60 and wire 61. Hence, as soon as the entire car or train leaves the rails of stretch A the circuit for relay D is closed so that semaphore S changes to clear indication and lamp L is 90 extinguished thereby indicating to following east-bound cars or trains that they may proceed through the stretch A at full speed. It is obvious that relay H may be omitted if desired, as shown in Fig. 2. In this view 95 the apparatus and circuits are the same as those shown in Fig. 1, except that relay H, the controlling circuits therefor, and the circuit controlled thereby are omitted. With the arrangement shown in Fig. 2, after an 100 eastbound car or train passes through the stretch, the signal device at siding B continues to indicate caution until the car or train has passed off of preliminary section P. 105

I will now explain the operation of the system shown in Fig. 1 during the movement of a car or train from east to west. The circuit for clear indication relay D' is from battery 10, through wire 26, back contact 27 of relay E, wire 62, back contact 63 of relay D, wire 64, circuit controller 14, wire 65, armature contact 66, wire 67, front contact 68, wire 69, relay D', wires 70 and 42 to battery 10. It will be noted that when 110 the preliminary section P is unoccupied this circuit is open both at relay D and at circuit controller 14 because semaphore S is in the clear position. As the car or train enters the preliminary section P, it opens the circuit for relay D at armature contact 35 of track relay c (relay H being now open) thereby changing semaphore S to the danger indication and closing circuit controller 14. The circuit for relay D' is then closed so 115 that this relay closes and thereby closes the circuit for semaphore S' which then changes to the clear indication, provided of course that no car or train is present in the stretch A. As the west-bound car or train enters 120 125 stretch A, it opens track relay b, thereby changing semaphore S to the danger indication and closing circuit controller 14. The circuit for relay D' is then closed so that this relay closes and thereby closes the circuit for semaphore S' which then changes to the clear indication, provided of course that no car or train is present in the stretch A. As the west-bound car or train enters 130

the stretch A, it opens track relay *b* thereby deenergizing relay D'. Relay D' is provided with a front contact 72 which is constructed like contact 44 of relay D hereinbefore described; hence, in the interval between the time the back contact 68^a closes and front contact 72 opens an energizing circuit for relay E' is closed, this circuit being the same as that just traced for relay D' to armature 68, then through wire 71, armature contact 72, wires 73 and 74, relay E', wires 75 and 42 to battery 10. Relay D' is, like relay D, provided with a back contact 21 which closes before front contact 72 opens, so that as relay D' opens it closes a holding or stick circuit for relay E' which circuit is from battery 11, through wire 20, armature contact 21, wire 76, armature contact 77, wire 74, relay E', wires 75 and 42 to battery 11. Hence as the car or train enters the stretch A, semaphore S' changes to danger indication and lamp L illuminates; and these indications are maintained until the car or train leaves the track circuit A at the west end. Of course semaphore S continues to indicate danger as long as the car or train occupies stretch A.

It will be noted that the circuit for relay D includes circuit controller 15 which is closed only when semaphore S' is at danger and it will also be noted that the circuit for relay D' includes circuit controller 14 which is closed only when semaphore S is at danger; this insures that only one of the semaphores S or S' can indicate "clear" at the same time. If the arrangement of control is such that both signaling devices indicate proceed, when no car or train is in the stretch A, these circuit controllers operated by the semaphores would of course be omitted, as shown in Fig. 4 hereinafter described.

With the form of signaling system shown in Fig. 1 the operation of trains may be as follows: When a west-bound car or train proceeds through the preliminary section P and approaches the siding C, if the driver finds that the signaling device at this siding indicates either "clear" or "caution" he will 45 continue on the main track, it being unnecessary to enter siding C. If however, the driver finds that this signaling device indicates "danger", he will enter the siding C and there wait until the car or train which is approaching through stretch A passes by. Then, with the arrangement of control here 50 shown, the car or train in the siding waits until the other car or train has time to pass entirely out of preliminary section P, and it 55 then backs out of the siding into preliminary section P. In so doing, if the stretch A is then clear it causes semaphore S' to indicate clear and it may then proceed through the stretch A. When an east-bound car or train 60 approaches siding B, if the driver finds that

the signaling device at this siding indicates "clear" or "caution", he will proceed on the main track, it being unnecessary to enter the siding. If however the signaling device indicates "danger" he will enter the siding B 70 and wait until the west-bound car or train which is in the stretch A passes by. As soon as the last named car or train leaves the stretch A, if the stretch is then clear, semaphore S will change to clear indication, 75 and the car or train on siding B may then proceed through the stretch A.

In Fig. 3 I have shown a duplication of the apparatus shown in Fig. 1, for the protection of two successive stretches A and M. 80 In this case the west end of stretch M forms the preliminary for stretch A, and the preliminary for stretch M is the adjacent portion of track to the east of stretch M. The operation of the apparatus shown in Fig. 3 85 will be evident from the foregoing explanation of Fig. 1.

In Fig. 1 it will be noted that relay H is energized by an east-bound car or train, but that it is not energized by a west-bound car 90 or train. As hereinbefore explained, I accomplish this control by providing an energizing circuit which includes a front contact of the track relay *c* for the preliminary section P and a back contact of the track relay 95 *b*; and by providing a holding or stick circuit which includes a back contact of track relay *c*. By means of this arrangement of control, the energizing circuit is closed by an east-bound car or train when track relay *b* 100 opens, but the holding or stick circuit is not closed until track relay *c* is opened.

In the arrangement of control shown in Figs. 1 and 2, when there is no car or train in the stretch A or in the preliminary section P, semaphore S indicates clear and semaphore S' indicates danger, and both lamps are extinguished. When a west-bound car or train enters the preliminary section P it causes semaphore S to change to danger 105 and semaphore S' to change to clear. When the stretch A is occupied by a car or train moving in either direction, the semaphores at both ends of the stretch are in the danger position, and the lamp ahead of the car or 110 train is extinguished indicating to cars or trains moving in the opposite direction toward the stretch to stop; but the lamp behind the car or train is illuminated indicating to succeeding cars or trains that they 115 may follow through the stretch under caution.

In the modification shown in Fig. 4, both semaphores S and S' normally indicate clear, because circuit controllers 14 and 15 are 120 omitted and the circuit for relay D' is not controlled by a back contact of relay D. The operation of the apparatus shown in Fig. 4 125 will be apparent from the foregoing explanation of Fig. 1.

It is obvious that other arrangements of normal aspects of the signals may be provided for as desired.

Although I have herein shown and described only a few forms of railway signalling systems embodying my invention, it is understood that various changes and modifications may be made therein within the scope of the appended claims without departing from the spirit and scope of my invention.

Having thus described my invention, what I claim is:—

1. In combination, a stretch of railway track, a signaling device adjacent one end of the stretch, a track relay normally energized but opened by the presence of a car or train in the stretch adjacent the said end, and relay including a front and a back contact, a relay controlled by the front contact of the said track relay, and having a front contact which, when the relay is deenergized by the opening of the track relay, remains closed until after the back contact of the track relay has closed, a caution indication relay for the control of the signaling device, an energizing circuit for the caution indication relay including the back contact of the track relay and the said front contact of the second relay whereby when a car or train enters the stretch from the said end the caution indication relay is energized during the interval between the opening of the track relay and the opening of the second named relay, means controlled by the second named relay for holding the caution indication relay energized as long as the second named relay remains open, and means controlled by the entrance of a car or train upon the stretch from the opposite end for opening the second named relay but not closing the caution indication relay.

2. In combination, a stretch of railway track, a signaling device located adjacent one end of the stretch and adapted to indicate danger, caution and clear, a clear indication relay and a caution indication relay for the control of said signaling device, a track relay operated by the presence of a car or train in the stretch adjacent the said end and having a front and a back contact, a circuit for the clear indication relay controlled by the front contact of the track relay, said clear indication relay having a front contact which when the relay is deenergized by the opening of the track relay remains closed until after the back contact of the track relay has closed, an energizing circuit for the caution indication relay including the back contact of the track relay and the said front contact of the clear indication relay whereby when a car or train enters the stretch from the said end the caution indication relay is energized during the interval between the operation

of the track relay and the opening of the clear indication relay, means controlled by the clear indication relay for holding the caution indication relay closed as long as the clear indication relay remains open, and means controlled by the entrance of a car or train upon the stretch from the opposite end for opening the circuit of the clear indication relay before the car or train reaches the point where it controls the said track relay.

3. In combination, a stretch of railway track, a signaling device adjacent one end of said stretch adapted to indicate danger, caution and clear, a clear indication relay and a caution indication relay for the control of said signaling device, a track relay normally closed but opened by the presence of a car or train in the stretch adjacent the said end and having a front and a back contact, a circuit for the clear indication relay controlled by the front contact of the track relay, said clear indication relay having a front contact which when the relay is deenergized by the opening of the track relay remains closed until after the back contact of the track relay has closed, an energizing circuit for the caution indication relay including the back contact of the track relay and the said front contact of the clear indication relay whereby when a car or train enters the stretch from the said end to energize the caution indication relay during the interval between the opening of the track relay and the opening of the clear indication relay, a holding or stick circuit for the caution indication relay controlled by the clear indication relay and arranged to be closed after the caution indication relay has become closed and before the said front contact of the clear indication relay opens, and means controlled by the entrance of a car or train upon the stretch from the opposite end for opening the circuit of the clear indication relay before the car or train reaches the point where it opens the said track relay.

4. In combination, a stretch of railway track, a signaling device adjacent one end of said stretch adapted to indicate danger, caution and clear, a clear indication relay and a caution indication relay for the control of said signaling device, a track relay normally closed but opened by the presence of a car or train in the stretch adjacent the said end and having a front and a back contact, a circuit for the clear indication relay controlled by the front contact of the track relay, the clear indication relay having a front contact which when the relay is deenergized by the opening of the track relay remains closed until after the back contact of the track relay has closed, an energizing circuit for the caution indication relay, which circuit is controlled by the

- back contact of the track relay and the said front contact of the clear indication relay whereby when a car or train enters the stretch from the said end the caution indication relay circuit is closed during the interval between the opening of the track relay and the opening of the clear indication relay and is again opened by the opening of the clear indication relay, a holding 10 or stick circuit for the caution relay which holding circuit is controlled by the clear indication relay and is closed before the said energizing circuit is opened by the opening of the clear indication relay, and means controlled 15 by the entrance of a car or train upon the stretch from the opposite end for opening the circuit of the clear indication relay before the car or train reaches the point at which it opens the said track relay.
- 20 5. In combination, a stretch of railway track, a signaling device adjacent one end of said stretch adapted to indicate danger, caution and clear, a clear indication relay and a caution indication relay for the control 25 of said signaling device, a track relay normally closed but opened by the presence of a car or train in the stretch adjacent the said end, a circuit for the clear indication relay controlled by a front contact of the 30 track relay, an energizing circuit for the caution indication relay including a back contact of the track relay and a front contact of the clear indication relay, the track relay being arranged to close the back contact before the front contact of the clear 35 indication relay opens, a stick circuit for the caution indication relay including a back contact of the clear indication relay and a front contact of the caution indication relay, the said back contact of the clear indication relay being arranged to close before the said front contact of that relay opens, whereby the caution indication relay is closed and held closed by the entrance of a 40 car or train upon the stretch from the end at which said signaling device is located, and means controlled by the entrance of a car or train upon the stretch from the opposite end for opening the circuit of the clear 45 indication relay before the car or train reaches the point at which it opens the said track relay.
- 50 6. In combination, a stretch of railway track, signal devices adjacent the ends of said stretch each adapted to indicate danger, caution and clear, a clear indication relay and a caution indication relay for each signal device, a plurality of track relays for the stretch of track, a circuit for each clear indication relay each of which circuits is controlled by all of the track relays, an energizing circuit and a holding 55 circuit for each caution indication relay, each of which circuits is controlled by the 60 corresponding clear indication relay, means

controlled by the track relay first operated by the entrance of a car or train upon the stretch for closing the energizing and the holding circuits of the caution indication relay for the entering end before the clear 70 indication relay for that end opens, the clear indication relay for the other end of the stretch being opened or held opened by the operation of the said first operated track relay.

75 7. In combination, a stretch of railway track, a signaling device adjacent one end of the stretch and adapted to indicate danger, caution and clear, a clear indication relay and a caution indication relay 80 for the control of said signaling device, a track relay normally energized but opened by the presence of a car or train in the stretch adjacent the said end and having a front and a back contact, a circuit for the clear indication relay including the front contact of the track relay, the clear indication relay having a front contact which when the relay is deenergized by the opening of the track relay remains closed until after 85 the back contact of the track relay has closed, means for holding said circuit open by the presence of a car or train in the portion of the stretch where such car or train does not influence the said track relay, an energizing circuit for the caution indication 90 relay controlled by the back contact of the track relay and the said front contact of the clear indication relay whereby when a car or train enters the stretch from the said 95 end the caution indication relay is energized, said contacts and connections being inoperative to energize the caution indication relay when the clear indication relay has first been opened by a car or train which 100 entered the stretch from the opposite end, and a holding or stick circuit for the caution indication relay controlled by the clear indication relay and arranged to be closed after the caution indication relay has closed. 110

8. In combination, two track relays successively operated by the passage of a car or train, a railway signaling device, an auxiliary signal relay for the control of said signaling device, an energizing circuit for the auxiliary signal relay including a back contact of one of the track relays and a front contact of the other track relay, and a holding circuit for the auxiliary signal relay including a back contact of the second mentioned track relay and a front contact of the auxiliary signal relay. 115

9. In combination, two track relays successively operated by the passage of a car or train, a railway signaling device, an auxiliary signal relay for the control of said signaling device, an energizing circuit and a holding circuit for the auxiliary signal relay, contacts and connections controlled by the track relays and acting when the track 120 125 130

- relays are operated by the passage of a car or train in one direction to close the energizing circuit when the first track relay is operated and to close the holding circuit when 5 the second track relay is operated, said contacts and connections being inoperative to close the holding circuit when the track relays are operated by the passage of a car or train in the other direction.
- 10 10. In combination, a stretch of railway track, a signal adjacent one end of the stretch, a track circuit for the stretch including a track relay opened by a train in the said end of the stretch, said relay comprising a front and a back contact, a relay controlled by said front contact and also comprising a front and a back contact, a third relay for controlling said signal, an energizing circuit for said third relay including the back contact of the track relay and the front contact of the second relay, and a holding circuit for the third relay including the back contact of the second relay.
- 15 11. In combination, a stretch of railway track, a signal device adjacent one end of the stretch adapted to indicate danger, caution and clear, a clear indication relay and a caution indication relay for controlling said device, a track circuit for the stretch including a track relay opened by a train adjacent the said end, said relay comprising a front and a back contact, a circuit for the clear indication relay controlled by the front contact of the track relay, an energizing circuit for 20 the caution indication relay including the back contact of the track relay and a front contact of the clear indication relay, a hold-

ing circuit for the caution indication relay including a back contact of the clear indication relay, and means controlled by a train 40 in the other end of the stretch for opening the circuit for the clear indication relay.

12. In combination, a stretch of railway track, a track circuit for the stretch including a track relay comprising a front and a 45 back contact, a second relay controlled by the front contact of the track relay, a third relay, an energizing circuit for the third relay including the back contact of the track relay and a front contact of the second relay 50 and a source of current, a holding circuit for the third relay controlled by the second relay, and a signal controlled by the third relay.

13. In combination, a relay having a front 55 and a back contact, means for controlling said relay, a second relay controlled by the front contact of the first relay and comprising a front and a back contact, a third relay, an energizing circuit for the third relay including the back contact of the first relay and a front contact of the second relay and a source of current, a holding circuit for the 60 third relay including the back contact of the second relay and a front contact of the third relay, and a signal controlled by the third relay.

In testimony whereof I affix my signature in presence of two witnesses,

HENRY W. GRIFFIN.

Witnesses:

A. L. VENCILL,
M. S. KIRKLAND.

It is hereby certified that in Letters Patent No. 1,298,693, granted April 1, 1919, upon the application of Henry W. Griffin, of New York, N. Y., for an improvement in "Railway Signaling," errors appear requiring correction as follows: Page 4, line 19, claim 1, for the word "and," first occurrence, read *said*; same page, line 98, claim 3, strike out the words "to energize," and same line, after the word "relay" insert the words *is energized*; and that the said Letters Patent should be read with these corrections therein that the same may conform to the record of the case in the Patent Office.

Signed and sealed this 22d day of April, A. D., 1919.

[SEAL.]

F. W. H. CLAY,
Acting Commissioner of Patents.
